GAS-COMPRESSOR.

1,299,211.

Specification of Letters Patent.

Patented Apr. 1, 1919.

Application filed January 5, 1917. Serial No. 140,678.

To all whom it may concern:

Be it known that I, CHARLES R. NEESON, a citizen of the United States, residing at New Rochelle, New York, have invented the following described Improvements in Gas-Compressors.

The invention consists in the general organization and the arrangement of parts in reciprocating compressors for ammonia gas and other fluids, enabling such apparatus to operate at high speed and with high volumetric efficiency and affording other advantages as hereinafter made apparent.

In the accompanying drawings:

15 Fig. 1 is a general longitudinal section through the cylinder of an example and preferred form of the compressor;

Fig. 2 is a cross section on line II—II; and

20 Fig. 3 a cross section on line III—III of Fig. 1.

The compressor cylinder 1 is closed at both ends by separate attached heads 2 each of which projects into the cylinder and is 25 appropriately cooled by circulation of water in its interior spaces. The piston 3, is double-acting and about one-half the length of the cylinder, and is reciprocated by its piston rod from a crank driven cross-head 4, and its stroke is such that it approaches close 30 to the inner faces of the cylinder heads at the end of its motion in each direction, thus working with a very slight clearance. The inlet ports 5 are disposed on the same side 35 and at opposite ends of the cylinder 1, being in the present case on the upper side, and they overlap the junction of the cylinder heads with the cylinder so that their central axes thus approximately coincide with the 40 clearance spaces at each end. In these positions they are partly overrun by the piston, as indicated in the drawing, and the inwardly projecting parts of the cylinder heads directly opposite the openings are cut away as 45 shown at 6 to avoid obstructing the inward flow from the ports.

The outlet ports 7 are similarly disposed in the opposite or lower side of the cylinder, each being thus well removed from its co- 50 operating suction port. The valve members proper are marked 8, and are desirably of the plate, or thin disk type, as indicated so as to have the least possible inertia, the inlet valves of course opening inwardly and 55 the outlet valves outwardly. There are one

or more intake and one or more outlet valves at each end of the cylinder, all centered to the clearance space, thus utilizing the full circumference of the clearance space and providing for the minimum valve resistance 60 to the inflowing gas. The ammonia to be compressed enters through the induction pipe 9 into the suction space or gas passage 10 formed between the upper side of the cylinder and a surrounding casing wall 11. 65 This passage serves to conduct the gas to the suction valves at both ends. Midway between the suction valve ports 5 and preferably in line with the induction pipe 9, as shown the cylinder 1 is provided with a 70 transverse or annular row of additional inlet ports 12 uncovered by the piston when at the extreme limit of its stroke in both directions, and the gas is admitted to such ports from the passage 10 through lateral branches 75 13 of the latter. It will be noted that the cylinder proper and the surrounding wall members forming the suction passage and its branches above referred to are formed as a single casting although that could obviously be otherwise.

During the initial part of the suction stroke, the gas is drawn into the compressor cylinder through the suction valves at one end or the other and thereby a forward 85 surge of gas is produced in the induction pipe 9 which is maximum at about the middle of the suction stroke or where the crank-driven piston is moving at its maximum velocity. This surge of gas persists while the 90 piston is approaching its stroke limit, and it is the purpose of the auxiliary ports 12 to allow the inflowing gas free access to the cylinder therethrough under the effect of its momentum. The said auxiliary ports are 95 therefore, disposed directly opposite the outlet of the induction pipe 9, as above described and the latter though not fully illustrated is arranged to lead straight, or with easy curves, to the said suction space 10, so 100 that the forward rush of gas may push as much as possible into the cylinder thereby increasing the density of the charge drawn in and consequently enhancing the ensuing compression. The additional amount of gas 105 thus introduced encounters less resistance to entrance than the main part of the sucked in charge, since it does not have to overcome the resistance of the valve springs and for the same reason the suction valves are per- 110

mitted to close quickly since the interior and exterior pressures are instantly balanced. By reason of the high speed of the piston the auxiliary ports are closed before 5 appreciable outflow can commence, the maximum efficiency being obtained only when the piston speed bears the necessary relation to the other parts to accomplish this result. An appropriate speed for the design shown 10 is 200 crank revolutions per minute.

The outlet valves 7 discharge into a common outlet space 14 formed between the under side of the cylinder and a jacket wall 15 and the gas is led therefrom through the 15 force pipe 16 to the condensers or other place of use. The outlet space 14 is formed also, in one piece with the cylinder as in the case of the suction space 10. The lower part of the compressor cylinder, and outlet space 20 especially at the ends, is arranged to be cooled by the circulation of water in any desirable way through the heads and side wall, the detail of the circulating passages being, however, unimportant to the present 25 invention and therefore not specially illustrated.

Claims:

1. A reciprocating gas compressor, comprising in combination with the cylinder, 30 piston, normal suction valve and induction pipe to supply the same and an auxiliary inlet port also supplied from said pipe and through which auxiliary port an additional charge of gas is delivered into the cylinder, 35 this extra charge moving into the cylinder under the momentum imparted to it by the suction stroke of the piston, as distinguished from a suction charge.

2. A gas compressor comprising a cylinder with removable cylinder heads and a suction valve disposed at the junction of the cylinder and the head, in part overlying the head and in part overrun by the piston, in combination with an auxiliary inlet port 45 uncovered by the piston at the end of its suction stroke and an induction pipe supplying said valve and inlet port.

3. In a gas compressor, a compressor cylinder, a suction valve leading thereto and 50 partly overrun by the piston, and an inlet

port uncovered by the piston at the end of its suction stroke, in combination with a suction space extending alongside the cylinder and supplying said suction valve and inlet port.

4. A double acting gas compressor comprising a cylinder having suction valves at its opposite ends and auxiliary inlet ports at its middle, in combination with a piston arranged to partly overrun said valves and 60 to uncover said inlet ports at the ends of its suction stroke in both directions and an induction pipe supplying both said valves and said uncovered ports.

5. A gas compressor comprising a compressor cylinder with suction valves disposed on the same side thereof and at its ends and having discharge valves disposed at the opposite side and at the ends, all of said valves being partly overrun by the piston in its compression stroke, in combination with auxiliary inlet ports uncovered by the piston at the end of its suction stroke, and a single induction pipe supplying said suction valves and auxiliary inlet ports.

6. A compressor for ammonia gas, comprising in combination with the cylinder and piston, the normal suction valve and an auxiliary inlet port, both connected to the same gas receiving space, and an induction pipe 80 connected to said space, whereby the forward surge of gas flowing into the cylinder by way of the suction valve will force some of the gas into the cylinder through the auxiliary inlet port.

7. A compressor for ammonia gas, comprising in combination with the cylinder and piston, the normal suction valve and an auxiliary inlet port, both connected to the same gas receiving space, and an induction pipe 90 connected to said space whereby the gas in passing to the suction valve will flow over the said auxiliary inlet port, said port being opened near the end of the stroke of the piston to admit a charge of gas to the cylinder 95 in addition to the charge admitted by way of the suction valve.

In testimony whereof, I have signed this specification.

CHARLES R. NEESON.
